UNITED STATES PATENT OFFICE.

ELLWOOD C. HALLER, OF EAST RUTHERFORD, NEW JERSEY.

PRINTER'S CHASE FOR STORAGE.

Application filed February 24, 1926. Serial No. 96,339.

My present invention has to do with printers' chases; and it consists in the chase possessed of the practical advantages hereinafter ascribed to it.

5 The invention in all of its details will be fully understood from the following description and claims when the same are read in connection with the drawings, accompanying and forming part of this specification, 10 in which:—

Figure 1 is a plan view of the chase constituting the preferred embodiment of my invention.

Figure 2 is a detail view showing a length 15 of metallic tubing as it appears precedent to being incorporated in my novel chase.

Figure 3 is an enlarged fragmentary view 20 illustrating the manner in which the lengths of the tubes are occupied with wood sections or other appropriate filler sections, and the manner in which the corners of the rectangular frames formed by the tubes are reinforced through the medium of metallic or alloy reinforcing blocks.

25 Figure 4 is an enlarged, fragmentary section taken in the plane indicated by the line 4—4 of Figure 1.

Figure 5 is a fragmentary view making 30 clear the fact that my novel chase is more than type high in accordance with the material feature of my invention.

Figure 6 is a detail view taken at right angles to Figure 3 and showing the manner in which the reduced ends of the section of 35 each corner reinforcement are lapped.

Similar numerals of reference designate corresponding parts in all of the views of the drawings.

Among other elements my novel chase 40 comprises a tube 1, rectangular in cross-section, Figure 4, and formed of brass or other appropriate sheet metal. The tube 1 is continuous, Figure 2, is provided with miter ends 2 and is notched at intermediate points in its length as designated by 3 for the forming of the three miter joints of the chase in addition to the joint formed by the confronting ends 2.

In addition to the tube 1, the chase 45 comprises filler lengths 4, preferably of wood, and corner reinforcements each of which is formed of two sections of metal, alloy or other appropriate material. The corner reinforcements are identical in construction, 55 and therefore a detailed description of the one shown in Figures 3 and 6 will suffice to

impart a definite understanding of the four. By comparison of Figures 3 and 6, it will be readily understood that the corner reinforcement referred to is made up of a section 1^a 60 with a reduced end 1^b, and a section 1^c with a reduced end 1^d, the said sections 1^a and 1^c being arranged at right angles to each other, and the reduced ends 1^b and 1^d being disposed in lapped relation. The walls of the 65 tube 1 are made as thin as possible, and the wood fillers 4 serve to preclude or prevent collapse of the said walls and to lend rigidity to the walls and to the chase as a whole. In this the wood fillers 4 are materially as 70 assisted by the metallic or alloy corner reinforcements, and in this latter connection it will be understood that the two sections that enter into each corner reinforcement are arranged as shown, and each corner of the 75 chase, formed in the manner described, electrically welded, riveted, or otherwise joined so that at each corner, there is a solid inseparable joint. Manifestly such joint lends increased stiffness and strength to the chase 80 as a whole and preserves the rectangular form of the same.

In present practice, many of the forms run upon small high-speed presses are expensively time consuming to lock to register. 85 In the case of supplementary runs it would be economical if this lock-up could be preserved. The cost of the standard below-type-high chases and the racks necessary for their 90 accommodation necessitate the breaking-up of these forms because any advantage gained by holding them in chase is overcome by the tie-up of investment in the chases and the consumption of room and cost of the racks necessary for their accommodation. The 95 forms must necessarily be relocked for supplementary runs. The elimination of the expense is desirable. It is to be understood, therefore, that it is an accomplishment of my invention that this end may be obtained by 100 providing a chase capable of being cheaply manufactured, light of weight but of sufficient strength for the purpose, and of being more than type-high so that a multiplicity of such chases may be piled or stacked together 105 without injury to their contents and so that no rack or other special fixture is needed to accommodate them. This invention, therefore, provides a means to economically preserve the lock-up and register 110 of printers' forms and to conveniently store them between runs, the change from one type

of chase to the other being facilitated by mere loosening of the quoins before the change is made and tightening them thereafter without in any manner disturbing the 5 justification of the form proper, the two types of chases having approximate inside measurements.

It will be apparent from the foregoing that the chase higher than type-high constitutes an important feature of my invention, and that my novel mode of reinforcing the corners of and insuring the rigidity of the tube 1 is another important feature of the invention as is the employment of fillers 10 in the lengths of tubes between the reinforced joints, the said fillers lending the necessary rigidity or stiffness to the portion 15 of the chase intermediate of the joint reinforcements.

20 I have specifically described the preferred embodiment of my invention in all of its details in order to impart a definite understanding of the said embodiment. I do not desire, however, to be understood as limiting myself to the precise construction and relative arrangement of parts as disclosed, my invention being defined by my appended 25 claims within the scope of which changes in form or structure and in arrangement may 30 be made without departure from my invention.

Having described my invention, what I claim and desire to secure by Letters-Patent, is:—

35 1. As a new article of manufacture, a printer's chase greater in height than the standard height of type for the purpose set forth.

40 2. A printer's chase comprising a continuous metallic tube forming a rectangular frame, metallic reinforcements in the corner portions of said tube, and fillers snugly occupying the portions of the tube intermediate of said corner reinforcements.

3. A printer's chase comprising a continuous metallic tube forming a rectangular frame, metallic reinforcements in the corner portions of said tube, and fillers snugly occupying the portions of the tube intermediate of said corner reinforcements, the joints of 50 the tube at the corners of the frame being mitered, and the said corner positions of the tube and the said metallic reinforcements being 55 permanently joined.

4. A printer's chase comprising a continuous metallic tube reduced to a frame of rectangular configuration, metallic reinforcements in the corner portions of the frame, and fillers in the frame and intermediate of 60 said corner reinforcements, each corner reinforcement being made up of sections disposed at right angles to each other and lapped, and the said tube and the sections of the corner reinforcements being permanently joined, or connected. 65

5. A printer's chase comprising a continuous metallic tube reduced to a frame of rectangular configuration, metallic reinforcements in the corner portions of the frame, and fillers in the frame and intermediate of 70 said corner reinforcements, each corner reinforcement being made up of sections disposed at right angles to each other and lapped, and the said tube and the sections of the corner reinforcements being permanently 75 joined or connected; the said tube, the sections of the corner reinforcements and the fillers being of rectangular cross section, and the tube in cross section being of greater 80 height than the standard height of type. 85

6. The improvement in the printing art which consists in securing type in a chase of greater height than the type, whereby a plurality of chases may be superposed without injury to the contents.

In testimony whereof I affix my signature.

ELLWOOD C. HALLER.
